UNITED STATES PATENT OFFICE

MAURICE GOUDARD, OF NEUILLY SUR SEINE, FRANCE, ASSIGNOR TO SOCIÉTÉ ANONYME SOLEX, OF NEUILLY SUR SEINE, FRANCE, A SOCIETY OF FRANCE

CARBURETOR

Application filed November 20, 1929, Serial No. 408,634, and in Belgium November 29, 1928.

The present invention relates to carburetors and, more especially, to those of the so-called "submerged nozzle" type.

Submerged nozzle assemblies are generally composed of (Fig. 1) a calibrated orifice or nozzle positioned at the bottom of a discharge tube which communicates through a series of orifices at different levels with a surrounding well. The fuel in said well 10 serves primarily to supply additional fuel during acceleration of the motor. When said well is empty, air is drawn through said orifices at different levels to form an emulsive mixture with fuel supplied by the calibrated submerged nozzle of the discharge tube.

These assemblies are too well known to require more detailed description.

One of the objects of the invention is to 20 provide means for preventing a too rapid evacuation of wells of the type described in assemblies of this nature.

Other objects will appear in the course of the detailed description now to be given with 25 reference to the accompanying drawings, in which:

Fig. 1 is a diagrammatic section through one illustrative embodiment of the invention;

Fig. 2 represents, in a similar manner another possible form;

Fig. 3 is a detail of the nozzle assembly shown in Fig. 1;

Fig. 4 represents, in section, the form of nozzle illustrated in Fig. 2;

Figs. 5 and 6 show, in section, two other possible forms that the invention may take.

Referring to Figs. 1 and 3 of the drawings, there is shown a mixing chamber 1 controlled by a valve 2, a venturi 3, an auxiliary mixing 40 chamber 4 supplied with carburant from an auxiliary or low-speed nozzle 5, a float chamber 6 of current design supplying fuel via a passage 7 to auxiliary nozzle 5 and submerged nozzle 8, a passage 9 delivering emulsion to outlet 10 and provided with carburant via a plurality of orifices of the type 12, 13, 14, a well 11 an external envelope 15 having an air inlet 16 formed therethrough, and a ring 19 leaving a small annular space 18 between orifices 12 and 13. Ring 19 may pre-

sent a series of superposed capillary passages as shown or have an internal cylindrical wall.

It will be seen that the hereinabove described device differs from those now in current use only in the adjunction of ring 19. The latter, by restricting the section of the lower part of the well 11, interposes a capillary resistance to the emptying of the latter. If, then, during acceleration, the liquid in well 11 is drawn rapidly through orifices 13 and 14, its movement through orifice 12 is impeded by the capillary resistance offered by annular passage 18 and the suction exerted on nozzle 8 will rise to the maximum necessary to insure the maximum feed desired during the acceleration period.

In practise, it is found that the best results are obtained when the section of annular space 18 is at least as great as the total section of all the orifices 12 which it controls (for carburetors of current design passage 18 should be of the order of magnitude of a fraction of a millimeter). When the relative dimensions of elements 12 and 18 are thus chosen, air will not enter orifices 12 until the difference in pressures at inlet 16 (atmospheric) and in passage 9 is sufficient to overcome the capillary resistance of passage 18. In other words, the draining of well 11 down to the level of orifices 12 will be delayed long enough to permit an increased feed from nozzle 8 during acceleration.

The devices shown in Figs. 2 and 4, and in Figs. 8 and 9 differ only in details from the one already described.

In the structure shown in Figs. 2 and 4, auxiliary nozzle 5 receives fuel from well 11 and the restricting effect of ring 19 of Fig. 3 is obtained by forming an annular extension 17 on tube 9 so as to limit a capillary passage 18 having the same function as the one already described.

In the structure shown in Fig. 5, tube 9 not only carries an annular extension 17 but is of different internal section at the top and bottom.

The form of device represented in Fig. 6 differs from those shown in Figs. 4 and 5, in the substitution of an extension 17 formed

so as to present a series of superposed annular passages 18 whereby the capillary resistance is increased.

The invention is, of course, not to be taken as limited to the structures shown in any particular figure, thus; any one of the devices shown in Figs. 3 to 6 may function with auxiliary nozzles of the type shown in either Figs. 1 or 2, passage 9, shown as having a uniform internal diameter in Figs. 3 and 4, may be of diminished internal diameter at its lower end, as shown in Figs. 5 and 6; any one of passages 18, represented in Figs. 3 to 5 may be given the superposed form illustrated in Fig. 6 and vice-versa; etc.

What I claim is:

1. In a carburetor, a liquid fuel reservoir, a nozzle assembly comprising a calibrated nozzle communicating with said reservoir, said nozzle being below the normal level of liquid fuel in said reservoir, a first tube having a plurality of orifices in the walls thereof at different levels and positioned above said calibrated nozzle, and a second tube positioned outside said first tube, said second tube communicating with the atmosphere, said first and second tubes being formed so as to define reduced capillary annular sections of the space in the well positioned between successive levels of the orifices in the walls of the first, said annular capillary sections being positioned in series with one another between successive orifices in the wall of the first tube.
2. In a carburetor, a liquid fuel reservoir, a nozzle assembly comprising a calibrated nozzle communicating with said reservoir, said nozzle being below the normal level of liquid fuel in said reservoir, a first tube having a plurality of orifices in the walls thereof at different levels and positioned above said calibrated nozzle, and a second tube positioned outside said first tube, said second tube communicating with the atmosphere, said first and second tubes being formed so as to define reduced capillary annular sections of the space in the well positioned between successive levels of the orifices in the walls of the first tube, and a mixing chamber positioned to exert suction on said nozzle assembly.
3. In a carburetor, a liquid fuel reservoir, a nozzle assembly comprising a calibrated nozzle communicating with said reservoir, said nozzle being below the normal level of liquid fuel in said reservoir, a first tube having a plurality of orifices in the walls thereof at different levels and positioned above said calibrated nozzle, and a second tube positioned outside said first tube, said second tube communicating with the atmosphere, said first and second tubes being formed so as to define reduced capillary annular sections of the space in the well between the levels of the two orifices in the walls of the first tube which are nearer the bottom of said well.
4. In a carburetor, a liquid fuel reservoir, a nozzle assembly comprising a calibrated nozzle communicating with said reservoir, said nozzle being below the normal level of liquid fuel in said reservoir, a first tube having a plurality of orifices in the walls thereof at different levels and positioned above said calibrated nozzle, and a second tube positioned outside said first tube, said second tube communicating with the atmosphere, said first and second tubes being formed so as to limit capillary annular sections of the space in the well positioned between the levels of the orifices in the walls of the first tube, said capillary annular section being in series with one another.

4. In a carburetor, a liquid fuel reservoir, a nozzle assembly comprising a calibrated nozzle communicating with said reservoir, said nozzle being below the normal level of liquid fuel in said reservoir, a first tube having a plurality of orifices in the walls thereof at different levels and positioned above said calibrated nozzle, and a second tube positioned outside said first tube, said second tube communicating with the atmosphere, said first and second tubes being formed so as to define reduced capillary annular sections of the space in the well positioned between successive levels of the orifices in the walls of the first, said annular capillary sections being positioned in series with one another between successive orifices in the wall of the first tube.

In testimony whereof I affix my signature.

MAURICE GOUDARD.
